REFINING MINERAL LUBRICATING OILS

William J. McGill, Alton, Ill., assignor to Standard Oil Company, Chicago, Ill., a corporation of Indiana

Application May 9, 1934, Serial No. 724,674

2 Claims. (Cl. 196—18)

This invention relates to a process of refining mineral lubricating oils and particularly to mineral lubricating oils containing paraffin wax. One of the objects of the invention is to provide a method for removing paraffin and petro-
5 latum waxes from such oils. Another object of the invention is to remove asphaltic constituents from oils of the residual type, a combination deasphalting and dewaxing process. Still another object of the invention is to provide greater 10 economy in the deasphalting of residual oils than has heretofore been achieved.

The invention will be more clearly understood from the accompanying drawing which forms 15 a part of this specification and diagrammatically illustrates an elevational plan of my apparatus.

The drawing will be described in connection 20 with the operation of the process in the refining of a typical residual oil, in this case a 40% residue obtained from the distillation of midcontinent crude oil. This residual oil is introduced by line 16 into absorber 11 where it is brought into contact with hot propane vapors supplied by line 12, as will be hereinafter described. The 25 hot propane vapors pass upwardly through the absorber which may be provided with suitable contact means, such as baffle plates, bubble cap plates, etc. The hot propane vapors coming in contact with the residual oil condense and dissolve therein, serving to heat the oil to the desired temperature. The temperature of the entering propane vapors may be between 150 and 300° F. and the resulting mixture of propane and 30 residuum is withdrawn from the base of the absorber by line 13 at a temperature between 100 and 200° F.

Valved line 14 is provided for withdrawing any 35 uncondensable vapors. In the upper part of the absorber I may employ a cooling coil 15 suitably connected to a source of cooling water by line 16, discharging by line 17. By regulating the amount of cooling provided by cooling coils 15 the temperature of the outgoing mixture of residuum and propane is partly controlled. The 40 temperature of this mixture is also controlled to an extent by introducing liquid propane into the absorber by line 18. Liquid propane added in this way also serves to regulate the composition 45 of the mixture withdrawn from the absorber which should usually lie between one and one-half to five volumes of propane per volume of residuum.

The hot mixture of propane and residuum from 50 the absorber is forced by pump 19 through heat

exchanger 20 and into deasphalting drum 21 where a separation into two layers is allowed to take place. Heat exchanger 20 may be supplied by cooling water or steam as an additional means of controlling the temperature. The upper layer 5 consists of a solution of oil in propane and the lower layer consists of a solution of propane in the asphaltic constituents of the oil. The pressure in this drum will usually be about 200 pounds per square inch gage at 100° F. and about 10 600 pounds per square inch at 200° F. By regulating the temperature the amount of material extracted from the oil by the liquid propane can be regulated to any desired degree. It is preferred to operate at a temperature of about 150 15 to 160° F., with a dilution of about 3 to 1, at which temperature approximately 25–35% of the residuum is extracted, but at greater dilutions of oil with propane, this temperature will be 20 lower and vice versa.

The upper layer in separator 21 consisting of the propane extract is withdrawn by line 22 and passed through heat exchanger 23 into chilling chambers 24 and 25. The heat exchanger 23 may be employed to reduce the temperature to 25 some intermediate point, for example, 70–80° F., but it is preferred not to lower the temperature by this means to a point where any appreciable amount of waxy constituents in the oil are caused to separate. For this purpose, cold filtrate from 30 filter 31 subsequently described, may be forced by pump 34 through bypass lines 34a and 34b to and from heat exchanger 23. Chambers 24 and 25 are suitably heat insulated as is also 35 drum 21 where it is essential to prevent ingress or egress of heat from the surrounding atmosphere during the operation of the process.

Chilling chambers 24 and 25 are employed alternately in the following manner: propane 40 solution is charged into one chamber until it is filled approximately to two-thirds of its capacity. The inlet valve is then closed and the valve in one of the vapor lines 26 is opened gradually to allow propane vapors to pass into compressor 27 by which they are forced into line 12 previously described. By this means the pressure is gradually diminished in the chilling chamber and as a result part of the liquid propane is evaporated from the propane-oil solution, bringing about the lowering of the temperature to any 45 point desired. In order to obtain complete removal of the waxy constituents from the oil it is desirable to reduce the temperature by this means to approximately –40° F. It is important to regulate the rate of cooling, preferably 50

not to exceed approximately 3° per minute in order to promote larger crystal growth in the separating wax, resulting in higher filtration rates in the subsequent step to be described.

- 5 While one chilling chamber is being cooled in the above manner the stream from line 22 is diverted to the other chilling chamber. If desired additional liquid propane may be introduced into the stream from propane storage by 10 pump 28 and line 28a, providing an independent means of controlling the amount of propane in the cold slurry obtained in the chilling chamber is provided. Ordinarily this slurry should contain between 60 and 70% of propane.
- 15 The cold slurry from the chilling chambers is withdrawn by line 29 and forced by pump 30 into filter press 31 where the separated wax is removed. This press may be of the continuous type, employing a revolving filter element dipping 20 in a bath of the slurry with means for removing the wax from the filter element, washing the wax cake with additional propane, etc. If desired, a battery of batch filter presses may be employed in place of the continuous filter.
- 25 The wax is discharged by line 32 and the wax-free filtrate by line 33 and pump 34 by which it is introduced under pressure to propane recovery tower 35, equipped with a heating coil 36, by which the temperature is raised to a 30 point where substantially all the propane is evaporated from the filtrate under pressure. The vapors are discharged by line 37 and thence to condenser 38 where they are reliquefied and collected in storage tank 39, suitably maintained under 35 pressure. If desired, part of the propane vapors may be diverted by valve 40 and line 41 to line 12, previously described. The filtrate which is now substantially free from propane is discharged by line 42 to a suitable storage tank for 40 refined lubricating stock. It may suitably be filtered through fuller's earth to further improve the color. It may also be further refined by treatment with sulfuric acid, extraction with selective solvents such as cresylic acid, beta-beta-dichlor-diethyl ether, etc.

45 Returning now to that portion of the oil remaining undissolved in the propane in separator 21, this is withdrawn by line 43 and forced by pump 44 into propane recovery tower 45. Heat 50 supplied by coil 46 drives off the propane which passes by vapor line 47 and line 37 to condenser 38, as previously described. The oil remaining after removal of propane is withdrawn by line 48 leading to storage tank not shown. This oil is 55 high in asphaltic constituents and is suitable mainly for the production of asphaltic road oils and fuel oil, or it may be used as a charging stock for certain types of cracking processes. When subjected to coking it produces a gasoline-containing 60 distillate useful for the manufacture of high octane value motor fuels.

65 Instead of using a residual oil as the charging stock for my process I may use mineral lubricating oil distillates, particularly those distillates of high viscosity of the order of 75 to 175 seconds Saybolt at 210° F. When using distillates of this type the oil obtained from tower 45 will contain very little asphaltenes and is suitable for certain uses as a high viscosity lubricating oil but will 70 ordinarily have a lower viscosity index than the oil obtained from tower 35. In fact, almost any desired viscosity can be obtained by regulating the temperature and propane concentration employed in separating drum 21. In general, the 75 more highly refined oil obtained from the upper

layer in drum 21 is of lower viscosity and suitable for the production of the lighter grades of lubricating oil when higher viscosity index and resistance to sludging is required. This lighter oil may be blended with the heavier oil from the lower layer to produce intermediate lubricating oil grades.

By suitably regulating the temperature and propane concentration in separator drum 21 it is possible to retain both the paraffin wax and petrolatum wax in solution in the propane forming the upper layer or, if desired, the temperature may be raised to a point between 180 and 200° F. at which point the paraffin wax will be extracted with the propane and the petrolatum wax will remain in the insoluble lower layer with the heavier oil. Under this condition it will be necessary to further dewax the oil in the lower layer and this may be done by reducing the temperature of this material to about 150° F. and treating with further quantities of liquid propane which will extract the petrolatum and reject most of the asphalt. Operating in this manner I may eliminate as much of the difficultly filterable heavy waxes from the propane-oil solution as desired, greatly facilitating the filtration of paraffin accompanying the oil in the propane layer withdrawn by line 22.

In the foregoing description of my invention have illustrated the process as applied to the refining of a 40% midcontinent residue. It should be understood, of course, that I may reduce the crude oil initially to a lower percent residue than 40%. For example, I may conveniently use 25% residue, especially when making the more viscous lubricating oils. The process is also applicable to other types of crude oil such as Pennsylvania, Texas, Salt Creek or California crudes, although the proportions of propane, temperature of asphalt separation, etc. will vary somewhat with different crudes, depending on the asphalt content of the residue.

Prior to charging the residue to my process may give it a preliminary treatment with sulfuric acid or I may subject it to extraction with selective solvent to remove oils of low viscosity index naphthenic characteristics. In this case when using residues refined in this manner I prefer to operate the process to produce two grades of lubricating oil, as previously described, when working with distillate products. My invention provides a particularly advantageous method of separating asphalt and/or heavy constituents from lubricating oils by absorbing hot propane vapors therein and subsequently refrigerating and dewaxing the oil, recompressing and cycling propane vapors from the dewaxing stage to the initial separating stage. Heat and power are both conserved by this operation and the oil refined with a minimum of handling and loss of propane. Throughout this specification I mention the use of propane as the diluent and solvent. However, it should be understood that I do not intend to limit the process to the use of pure propane as I prefer to use a commercial grade of propane which contains some ethane and normal and iso-butane, which constituents alter the properties of propane to some extent but do not interfere with the successful carry out of the process. Although I have described my process with respect to specific examples it is intended to be limited only by the following claims:

I claim:

1. The process of refining a viscous hydrocarbon residue comprising:

carbon lubricating distillate containing paraffin and petroliatum wax, which comprises absorbing hot propane vapors therein until the oil is separated into two phases; regulating the temperature between 160 and 200° F., whereby the oil is separated into a lighter phase containing easily filterable paraffin wax and a heavier phase containing a difficulty filterable petroleum wax; cooling and refrigerating said lighter phase; 10 then filtering crystallized wax from the refrigerated material and subsequently recovering the

propane contained therein; recovering the propane from said heavier phase; recompressing propane vapors and absorbing said vapors while still hot with the heat of compression in said original lubricating oil distillate.

2. The process of claim 1 wherein the propane is recovered from said oil phases by distillation under pressure and hot propane vapors produced thereby are absorbed directly in the lubricating oil stock charged to the process.

WILLIAM J. MCGILL.
